United States Patent Office

Des. 218,732

Patented Sept. 22, 1970

218,732

COMBINED BOTTLE AND CAP THEREFOR

Livingston C. Douglas, Leonia, N.J., assignor to Colgate-Palmolive Company, New York, N.Y., a corporation of Delaware

Filed May 23, 1969, Ser. No. 17,292

Term of patent 14 years

Int. Cl. D9—01

U.S. Cl. D9—117

FIG. 1

FIG. 2

FIG. 4

FIG. 1 is a side elevational view of a combined bottle and cap therefor embodying my new design, the opposite side being the same in appearance as the side shown;

FIG. 2 is an end elevational view thereof, the opposite end being the same in appearance as the end shown;

FIG. 3 is a top plan view thereof.

FIG. 4 is a bottom plan view thereof.

The dominant features of my design reside in the bottle portions as shown in the drawing.

I claim:

The ornamental design for a combined bottle and cap therefor, as shown and described.
